UNITED STATES PATENT OFFICE.

CLARENCE L. CHAPMAN, OF ERIE, PENNSYLVANIA, ASSIGNOR OF ONE-HALF
TO HENRY I. PETRIE, OF LITTLE FALLS, NEW YORK.

NUT-TAPPING MACHINE.

SPECIFICATION forming part of Letters Patent No. 444,062, dated January 6, 1891.

Application filed March 11, 1890. Serial No. 343,450. (No model.)

To all whom it may concern:

Be it known that I, CLARENCE L. CHAPMAN, of Erie, in the county of Erie and State of Pennsylvania, have invented a new and Improved Nut-Tapping Machine, of which the following is a full, clear, and exact description.

The object of the invention is to provide a new and improved machine for cutting the thread in punched blanks for nuts which will be simple and durable in construction, very effective and entirely automatic in operation, and will require no manual labor except filling the hopper with the blanks.

15 The invention consists in an automatic device for removing the nut-blanks singly from the hopper and delivering the same regularly in proper position to the tap.

The invention further consists of means 20 for automatically feeding the tap and lifting it; and it also consists of a mechanism for automatically removing the tap from the spindle to dump the threaded nuts.

The invention also consists of certain parts 25 and details and combinations of the same, as will be hereinafter fully described, and then pointed out in the claims.

Reference is to be had to the accompanying drawings, forming a part of this specification, 30 in which similar letters of reference indicate corresponding parts in all the figures.

Figure 1 is a plan view of a single machine. Fig. 2. is a sectional side elevation of the same on the line $x-x$ of Fig. 1. Fig. 3 is a 35 side elevation of the same. Fig. 4 is an elevation of the opposite side of the same with parts broken out. Fig. 5 is a plan view of the clutch mechanism with parts in section. Fig. 6 is a sectional end view of the same on 40 the line $y-y$ of Fig. 5. Fig. 7 is an enlarged sectional side elevation of the tap-holder. Fig. 8 is a sectional plan view of the same on the line $z-z$ of Fig. 7. Fig. 9 is an enlarged inverted plan view of the clamping device 45 for the tap. Fig. 10 is a face view of the cam-plate for the same. Fig. 11. is an enlarged sectional plan view of the feeding device; and Fig. 12 is an enlarged sectional side elevation of the tap-dumping mechanism.

The improved nut-tapping machine is 50 mounted on a suitably-constructed frame A, in the upper rear part of which is journaled the transversely-extending main driving-shaft B, carrying at one end a pulley B', connected with suitable machinery for imparting 55 a rotary motion to the said main driving-shaft B. On the latter is also secured a smaller pulley B², over which passes a quarter-turn belt B³, also passing over a pulley B⁴, secured on the vertically-arranged spindle C, mounted to 60 turn in suitable bearings formed in a bracket A', secured on the top of the frame A at its front end.

On the spindle C, above the pulley B⁴, is a loose flanged collar C', against the under side 65 of which presses a spring C², coiled on the spindle C and resting at its lower end on the web or hub of the pulley B⁴. The latter is held in place on the spindle by a collar C³, secured to the spindle, and on the top of which 70 rests the under side of the hub or web of the pulley B⁴. The spring C² serves to exert pressure against the pulley B⁴, and consequently the spindle C, when the latter is raised in an uppermost position, the collar C' striking 75 against the upper bearing on the bracket A', and a further upward motion of the pulley B⁴ then compressing the spring C².

On the lower end of the spindle C is held the tap-holder D, carrying the tap E, having 80 a long shank E', on the lower end of which are formed the usual cutting-threads E² for tapping the nuts. The shank E' is sufficiently less in diameter than the threads E², so that the nuts after being tapped can readily 85 slide on the said shank E'. The latter is provided on its upper end with a polygonal or square offset E³, adapted to pass into a correspondingly-shaped opening D³, formed in the lower part D² of the tap-holder D, which latter is made of the two parts D' and D², of which the part D² screws on the part D', and said part D' is secured to the lower end of the spindle C, as is plainly shown in Figs. 2 and 7.

On the upper end of the square offset E³ of the tap E is formed a semicircular annular recess E⁴, adapted to be engaged by pins D⁴,

held to slide radially in the lower part D² of the tap-holder, the outer ends of the said pins being secured to springs D⁵, secured on the said part D² of the tap-holder. The springs have the tendency to hold the pins D⁴ in an innermost position—that is, in contact with the annular recess E⁴—so as to hold the tap E in place in the holder D.

The extreme upper part of the tap-shank 10 E' is formed with a rounded-off head E⁵, as is plainly shown in Fig. 7. The under side of the lower part D² of the tap-holder D is provided with a cone-shaped recess D⁶, which permits the head E⁵ of the shank E' to be 15 readily guided into the opening E³ when the tap is reinserted in the tap-holder, as hereinafter more fully described.

On the spindle C, below the driving-pulley B⁴, is secured a bar F', forming part of the 20 lifting mechanism F for raising the spindle C to raise the tap E after one nut is tapped and has slipped onto the shank E' of the said tap, the tap being then ready to again engage the next following nut in order to tap 25 it. On the outer ends of this bar F' of the lifting device F are secured trunnions, to which are pivotally connected links F², pivotally connected with levers F³, which are in turn pivoted at F⁴ to the main frame A.

30 On the levers F³ are held friction-rollers F⁵, traveling on a cam G, secured on a transversely-extending shaft G', mounted to turn in suitable bearings in the frame A. On the shaft G' is secured a worm-wheel G², meshing 35 into a worm G³, secured on an inclined shaft G⁴, mounted to turn in suitable bearings in the main frame A, and provided at its upper end with a bevel gear-wheel G⁵, meshing into a bevel-pinion G⁶, secured on the main driving-shaft B. When the latter is rotated, a 40 rotary motion of the same speed is transmitted to the spindle C by the belt B³ and the pulleys B² and B⁴. At the same time a rotary motion is transmitted to the shaft G' by 45 the bevel gear-wheels G⁵ and G⁶, the shaft G⁴, and the worm G³ and worm-wheel G², but in such a manner that when the shaft B has made thirty-two revolutions the shaft G' has made one revolution. Every time the shaft 50 G' makes one revolution its cams G, engaging the friction-wheels F⁵ of the levers F³, cause the latter to swing upward so as to raise the spindle C, thereby lifting the tap E after one 55 nut is tapped and for the purpose of placing a new nut in place to be tapped when the spindle C again descends, as hereinafter more fully described.

On one outer end of the shaft G' is secured 60 an arm G⁷, carrying an adjustable finger G⁸, adapted to engage one of the teeth H' of a toothed wheel H, which carries on its face a pin H², adapted to engage an arm H³, secured on a transversely-extending shaft I, arranged below the shaft G' and mounted to turn in 65 suitable bearings in the main frame A. On the hub H⁴ of this arm H³ is mounted to turn loosely the toothed wheel H, previously men-

tioned, the said wheel H being turned the distance between two teeth at every revolution of the shaft G' by the finger G⁸, held on the arm G⁷, secured to the said shaft G'. The shaft I governs the dumping device J of the tap E and also the mechanism K for disconnecting the tap from its holder D.

On the shaft I is secured a cam-wheel I', on the periphery of which is held one arm of a bell-crank lever I², extending horizontally and fulcrumed on the main frame A. The other arm of the said bell-crank lever I² is formed like a shifting fork, and engages a clutch I³, mounted to turn with and to slide on the shaft I and adapted to engage a correspondingly-shaped clutch I⁴, formed on one face of a gear-wheel I⁵, held to rotate loosely on the shaft I. The gear-wheel I⁵ is in mesh with a 85 large gear-wheel I⁶, secured on the shaft G', the said gear-wheel I⁶ being about four times as large as the gear-wheel I⁵. A spring I⁷ is coiled on the shaft I between the hub of the cam I' and the smooth end of the clutch I³, 90 the said spring I⁷ serving to quickly force the clutch I³ in mesh with the clutch I⁴, when the bell-crank lever I² is free to shift—that is, when its arm passes suddenly over the back of the cam I'. 95

On the rear outer end of the shaft I is secured a cam-wheel L for operating the dumping device J, and the mechanism K, for disengaging the tap from the holder D. For the first purpose this cam L is provided on its outer face with a pin L', adapted to engage an arm J', extending from a lever J², fulcrumed at J³ on the outside of the main frame A. From this lever J² projects forward a segmental gear-wheel J⁴, meshing into a gear-wheel J⁵, secured on one end of a transversely-extending shaft J⁶, mounted to turn in suitable bearings arranged on the outside of the lubricating-box N, secured to the under side of the bed-plate of the main frame A, as is plainly shown in Figs. 1 and 4.

On the shaft J⁶ is secured a segmental arm O, adapted to pass over the slightly outwardly-curved end of the front of the lubricating-box N. On the outer end of this segmental arm O is secured a horizontally-extending part O', on the top of which is held the nut-holder O², provided with an opening O³, covered by a transverse bar O⁴, and through which passes the nut to be tapped by the tap E. The nut-holder O² is arranged to contain two nuts at a time, one being under the bar O⁴ and the other one alongside of it at the inner end of the holder and directly under the tap E. The holder O² is made removable 115 from the segmental arm O, so as to change it according to the size of the nuts to be tapped. When the segmental arm O is in the position shown in Fig. 2, the inner nut abuts against the end of the nut-holder and also on the sides of the same, so that its punched aperture will be in line with the tap E. Directly under this nut to be tapped are arranged openings 120 in the bottom of the nut-holder O², and also

in the part O', for the free passage of the threaded end E² of the tap E.

On the under side of the plate O' is arranged a clamping device P, adapted to engage the threaded end E² of the tap E whenever the latter is to be disengaged at its upper end from the holder D, and as is plainly illustrated in Fig. 12. This clamping device P is provided with a bolt P', on which are pivoted two jaws P² and P³, having segmental openings arranged opposite each other to conform to the diameter of the blade end E² of the tap E, as is plainly shown in Fig. 9. The two jaws P² and P³ are pressed toward each other by springs P⁴, secured to the under side of the plate O', and the said two jaws P² and P³ are held apart as long as the segmental arm O is in the position shown in Fig. 2 by their inner ends P⁵ engaging the inclined edge of arms N², formed on a fixed plate N³, secured to the inside of the front of the lubricating-box N. The downward motion of the tap E is limited by the fixed plate N⁴, extending horizontally in the lubricating-box N, as illustrated in Fig. 2. The two jaws P² and P³ are spread apart at their segmental openings, but their rear ends P⁵ engage the beveled arms N² of the fixed plate N³—that is, when the segmental arm O is in the position shown in Fig. 2 and the tap is ready to tap the nuts.

When the segmental arm O swings to remove the plate O' from the lubricating-box N, as hereinafter more fully described, then the rear ends P⁵ of the said jaws P² P³ are disengaged from the beveled arms N² of the fixed plate N³, so that the springs P⁴, pressing on the said jaws, close the same, so that they engage the blade end E² of the tap E and hold the same in position. The outer end of the opening O⁶ of the nut-holder is adapted to register, when the segmental arm O is in the position shown in Fig. 2, with a channel O⁶, arranged on the top of the lubricating-box N, the outer end of this channel being connected with the inclined chute Q' of the nut-feeding device Q.

Under the channel O⁶, and secured to the under side of the top of the lubricating-box N, is arranged a spring O⁷, forming at its free end an upwardly-extending lug O⁸, engaged by the under side of the plate O' when the segmental arm O is in the position shown in Fig. 2, so that the spring O⁷ is bent downward. The moment the segmental arm O swings upward and carries the plate O' with it then the compressed spring O⁷ springs upward and its lug O⁸ passes in front of the channel O⁶, so as to prevent the nuts from passing out of the said channel into the lubricating-box N. When the plate O' swings back again, it again presses out the lug O⁸ of the spring O⁷ to disengage the same from the opening of the channel O⁶, so that the nuts can again pass from the channel to the nut-holder O².

The gear-wheel J⁵ is not secured rigidly on

the shaft J⁶, but is held loosely thereon, and is connected with one end of a coiled spring J⁷, connected at its other end to a collar J⁸, secured on one outer end of the shaft J⁶, so that in case of accident the gear-wheel J⁵ can be rotated by the segment J⁴ without turning the shaft J⁶, but compressing the spring J⁷, it being understood that this would only take place in case the segmental arm O is locked in place by the tap E, as shown in Fig. 2. A spring J⁹ is coiled on the said shaft J⁶, and serves to insure the return movement of the shaft J⁶ after the nuts are dumped from the shank E' of the tap E, as hereinafter more fully described.

In the periphery of the cam L is formed a recess L², and on the said periphery is held to travel a friction-roller K', journaled in one end of a short arm K², secured on one end of a transversely-extending shaft K³, mounted to turn in suitable bearings in the main frame A. On the shaft K³ is secured a forwardly-extending lever K⁴, provided at its outer end with a ring K⁵, concentric with the spindle C. On this ring K⁵ is held to travel a friction-roller K⁶, journaled on one end of a lever K⁷, fulcrumed on the upper part D' of the tap-holder D and projecting with its inner end through a recess in the said part D', the inner end being provided with an offset K⁸, adapted to engage a slot D⁷, formed in a plunger D⁸, held to slide vertically in the part D' of the holder D. From this plunger D⁸ extends downward a pin D⁹, adapted to pass onto the head E' of the tap E, and serving to disengage the latter from the pins D⁴ and to press it out of the holder D², as hereinafter more fully described, preparatory to dumping the nuts which have accumulated on the shaft E' of the tap E.

The chute Q' previously mentioned is provided on its upper end with a twist Q² and is supported at its upper end on a lever Q⁴, fulcrumed loosely on a shaft S, mounted to turn in suitable bearings in the main frame A and arranged transversely below the main driving-shaft B. On this shaft S is secured a pulley S', over which passes a belt S², also passing over a pulley S³, secured on the shaft G', which, as previously described, is rotated from the main shaft B.

The rotary motion of the shaft G' is transmitted by the pulley S³, the belt S², and the pulley S' to the shaft S. On the latter is secured a wheel T, having a shoulder T' cut in its periphery, the said shoulder serving to take up one of the nuts from an inclined hopper U, in the lower narrow end of which fits part of the said wheel T, so that at every revolution of the wheel T its shoulder T' takes up one of the nuts in the hopper and carries and dumps it onto an inclined flange Q⁶, formed on a narrow chute Q⁷, inclined, as shown in Fig. 2, and secured to the lever Q⁴ and opening at its lower into the upper end Q² of the chute Q'. The lever Q⁴ is provided on its outer end with a curved projection Q⁵, adapted

to be engaged by a toothed wheel Q^8 , secured on the shaft G' and turning with the latter. The toothed wheel in passing over the projection Q^5 imparts a swinging motion to the lever Q^4 , so that the chute Q' is vibrated and a similar motion is imparted to the chute Q' , resting at its lower end on the top of the lubricating-box N at the end of the channel O^6 , as previously described. A nut taken up by 5 the shoulder T' falls flat onto the flange Q^6 , and from the latter, by the vibratory motion of the chute Q' , into the narrow channel of the latter in an upright position, as shown in Fig. 2. The nuts are successively delivered into 10 the upper end Q^2 of the chute Q' , which upper end, on account of its twist, turns the nut until it lies flat and slides down the said chute Q' into the channel O^6 and from the latter into the holder O^2 when the said holder registers with the said channel O^6 , as previously 15 described.

The operation is as follows: When the main driving-shaft B is rotated, the several mechanisms are set in motion in the manner presently to be described. When the machine starts, the cams G on the shaft G' , acting on the friction-rollers F^5 , raise the levers F^3 , which, by being connected with the spindle C , raise the latter, so that the tap E moves upward with the spindle and its lower threaded end E^2 is above the holder O^2 , which latter is then free to receive two nuts pressed into the holder from the series of nuts contained in chute Q' . The innermost nut is then in the proper position to be acted on by the threaded end E^2 of the tap, and as soon as the cams G have disengaged the friction-rollers F^5 the previously-compressed spring C^2 presses the spindle C downward and forces the lower threaded end E^2 of the tap E into the punched aperture of the respective nut, so that as the spindle C has a constant rotary motion the threaded end taps the nut in the usual manner and the nut, after having passed the threaded end, remains on the shank E' of the tap. When this takes place, the cams G again engage the friction-rollers F^5 to raise the spindle C , which latter and its tap E are moved upward, carrying the threaded end along. When the spindle is in its uppermost position, a new nut is shoved into place on the holder O^2 , and when the spindle again descends the second nut is threaded in the manner above described. This motion is continued until fifteen nuts have accumulated on the shank E' of the tap E . Now at every revolution of the shaft G' the finger G^8 moves the toothed wheel H the distance between two teeth, and as the wheel H is provided with fifteen teeth its pin H^2 engages the arm H^3 and carries the latter with it, so as to turn the shaft I . At the end of the fifteenth revolution of the shaft G' the shaft I has made one revolution, and at the same time the bell-65 crank lever I^2 drops off of the back of the cam I' , (see Figs. 6 and 5,) so that the spring I^7 ,

pressing on the clutch I^3 , throws the latter into mesh with the clutch I^4 , and as said clutch I^4 is constantly rotated from the large gear-wheel I^6 and the gear-wheel I^5 a rapid rotary motion is imparted to the shaft I by the said gear-wheels I^6 and I^5 . At the time when the cams G lift the spindle C the sixteenth time, as previously described, the cam L on the shaft I is in such a position that the friction-wheel K' travels up the incline L^2 of the said wheel L , whereby the lever K^4 , by its ring K^5 acting on the lever K^7 , swings the outer end of the same upward and the inner end K^8 downward, so as to press or hold the plunger D^8 in position while the spindle C , with its holder D , slides upward vertically. The pin D^9 now presses on the head E^3 of the tap E , so as to force the pins D^4 outward, which thus disengage the annular recess E^4 , whereby the shank E' is unlocked from the lower part D^2 of the holder D , and the square end E^3 of the shank slides out of the opening D^3 as the spindle C moves into its uppermost position. At this time the wheel L moves its pin L' into contact with the lever J^2 , so that the latter is turned until the pin L' slips over the segmental arm J^1 . As the said lever J^2 oscillates from the pivot J^3 , which is located a suitable distance below the shaft I , carrying the wheel L , the oscillation carries the lever out of the circular travel of the pin L' . The movement of the lever J^2 forces its segmental arm J^4 upward, so that the gear-wheel J^5 is turned, and by the connection of the latter with the spring J^7 , the collar J^8 , and the shaft J^6 the latter is given a half-turn, whereby the segmental arm O swings outward, carrying with it the tap E , which is freed at its upper end from the holder D , as previously described. As soon as the arm O commences to swing outward, the jaws P^2 and P^3 close by the action of the springs P^4 , and on account of being disengaged from the beveled lugs N^2 of the fixed plate N^3 the jaws P^2 and P^3 in closing clamp the threaded end E^2 of the tap E , so as to hold the latter in place on the plate O' , attached to the segmental arm O . When the shaft J^6 turns into the position shown in Fig. 12, the shank E' of the tap E extends downward, so that the nuts which had been held above the thread E^2 of the shank E' now slide off the latter onto the ground or a suitable receptacle located below the machine under the shaft J^6 . As soon as this has taken place the spring J^9 causes a return movement of the shaft J^6 at the time when the pin L' has left the arm J^1 of the lever J^2 , so that the shaft J^6 , with the said lever J^2 , returns to its former position, the tap E being free from all the tapped nuts. As soon as the tap again moves into its vertical position, as shown in Fig. 2, the jaws P^2 and P^3 again engage the shoulders N^2 of the fixed plate N^3 , and are thereby opened to release the tap E , and at the same time the upper end of the shank E' of the said tap is engaged by the downwardly-

sliding holder D, the conical end D⁶ of which guides the head E⁵ into the opening D³, the head finally passing over the spring-pressed pins D⁴, which latter again snap onto the annular recess E⁴, so as to lock the tap again to the holder D, as previously described. The next upward movement of the spindle C carries the tap along, a nut is again pushed into the holder O², which now again registers with the channel O⁶, in the manner above described, and the previously-described operation is repeated. When the shaft I is given one quick revolution by the gear-wheel I⁶ at the time the clutches I³ and I⁴ are in mesh and the revolution is almost completed, then the bell-crank lever I², by traveling up the steep inclined part of the cam I', (see Fig. 6,) commences to move the clutch I³ out of contact with the clutch I⁴; but the movement of the lever I² will barely disengage the clutch-teeth without leaving any clearance between the teeth. The additional movement for the shaft I is, however, furnished by the weight of the arm K² and the lever K⁴, which press at this time the friction-roller K' onto one side of the recess L² in the cam L, thus turning the shaft sufficiently to move the bell-crank lever to the highest point of its cam I', and thereby completely separating the two clutches I³ and I⁴, and giving plenty of clearance for the same while not in mesh. The friction-roller K' always stands in the lowest point of the recess L² of the cam L when the latter is not turned by the shaft I. When the friction-roller K' stands in its lowermost position, the lever K⁴ also hangs downward and its ring K⁵ does not affect the lever K⁷ and the plunger D⁸ when the spindle rises and falls, as above described, to tap the respective number of nuts for which the machine is constructed at every full revolution of the toothed wheel H. When the roller K' stands in the lowest point of the recess L² of the cam L, then the pin L' stands in its lowermost position, and when the cam L turns with the shaft I the said roller, in traveling up the steep side of the recess L², actuates the device for disengaging the tap from the holder D before the pin L' acts on the lever J² to turn the shaft J⁶, so that the tap is free from the holder D before the segmental arm O swings the tap to dump the tapped nuts, as above mentioned. It will be seen that should a blank nut with an opening too small for the size of the tap E used, or a nut not punched at all, come into the nut-holder O² under the tap, then the spindle C, carrying the tap, when it meets such an error, will simply be held in a raised position, with the lower end of the tap turning on top of the faulty nut. The other parts of the machine keep up their functions, however; but when the shaft J⁶ is to be turned by the segmental gear-wheel J⁴ turning the gear-wheel J⁵, the latter makes its half-revolution, but only compresses the spring J⁷ without turning the shaft J⁶. The faulty nut

can be easily removed at any time by the operator in charge of the machine.

In case an unpunched nut is in the holder under the tap E then the nut-feed wheel T still delivers at each of its revolutions a nut to the chute Q⁷; but as the chute Q³ is filled with nuts, the additional nuts passing down the chute Q⁷ fall over the upper end of the chute Q³ to the ground. This also takes place when the wheel T feeds the nuts faster as they are taken and threaded in the manner above described.

It is understood that a series of machines may be placed one alongside the other on the same frame, to be driven from the main driving-shaft B, it then not being necessary to provide a separate shaft I and clutch mechanism for each machine, as one will be sufficient to impart the necessary movement to a shaft J⁶, which will be common for the dumping mechanism of each machine. The several spindles C are then also connected with each other by a continuous bar instead of the trunnioned bar F', the said bar being connected at its ends with the links F³ of the single lifting mechanism, as shown and described. The shaft K³ will then carry a lever K⁴ for each spindle to disengage the tap from the respective spindle. The several movements of the series of machines will then be simultaneous. For different-sized nuts correspondingly-sized taps and feeding-chutes must necessarily be employed.

For nuts of a size larger than nine-sixteenths of an inch the spindle C is driven by gear-wheels instead of the belt B³ and pulley-connections, as such nuts require more power for threading.

Having thus fully described my invention, I claim as new and desire to secure by Letters Patent—

1. In a nut-tapping machine, the combination, with an inclined chute U, having the space between its side walls at its inner open end contracted, of a rotary wheel T, the inner portion of which enters said contracted space and provided with a toothless periphery having a notch forming a single radial shoulder T', to pick up one nut at a time and carry it outside of the hopper, substantially as set forth.

2. In a nut-tapping machine, a nut-feeding device comprising a wheel having a shoulder adapted to pick up and carry a nut, and a vibrating inclined chute having flanges onto which discharges the shoulder of the said wheel, substantially as shown and described.

3. In a nut-tapping machine, a nut-feeding device comprising a wheel having a shoulder adapted to pick up and carry a nut, a vibrating inclined chute having flanges onto which discharges the shoulder of the said wheel, and a second chute having a twisted upper end and into which discharges the said chute, substantially as shown and described.

4. In a nut-tapping machine, a spindle hav-

ing a tap-holder adapted to support the tap and a plunger within said holder to engage the upper end of the tap and push it out of the holder, substantially as shown and described.

5. In a nut-tapping machine, a spindle having a tap-holder adapted to support the tap, the spindle being held to slide vertically, in combination with a plunger for automatically disconnecting the tap when the said spindle moves upward, substantially as shown and described.

6. In a nut-tapping machine, a tap-holder having a polygonal recess for the reception of the polygonal end of the tap, and spring-pressed pins held to slide in the said holder and adapted to lock the tap in place in the said holder, substantially as shown and described.

15 7. In a nut-tapping machine, the combination, with a tap having a polygonal end formed with an annular semicircular recess, of a tap-holder having a polygonal recess for the reception of the polygonal end of the tap, 25 spring-pressed pins held to slide in the said holder and adapted to lock the tap in place in the said holder, and a plunger having longitudinal movement in the holder to engage the upper end of the tap and push its recessed end past the pins, substantially as 30 shown and described.

8. In a nut-tapping machine, the combination, with a tap having a polygonal end formed with an annular recess, of a tap-holder having a polygonal recess for the reception of the polygonal end of the tap, 35 spring-pressed pins held to slide in the said holder and adapted to lock the tap in place in the said holder, and a plunger held to slide in the said tap-holder to disconnect the said tap and holder, substantially as shown and described.

40 9. In a nut-tapping machine, the combination, with a swinging arm, of a nut-holder and a clamp to grasp the tap when the arm and attached holder and clamp are swung outward, substantially as set forth.

45 10. In a nut-tapping machine, the combination, with a swinging arm, of a nut-holder thereon, a normally-open tap-grasping clamp adjacent thereto and closing on the tap when the arm is swung outward, and a clamp opener or releaser in the path of the clamp when the arm with its attached holder and clamp are swung inward, substantially as set forth.

50 55 11. In a nut-tapping machine, the combination, with a lubricant tank or receiver, of a swinging arm mounted to swing into and out of the tank or receiver and provided with a nut-holder on its end within the tank, substantially as set forth.

60 12. The combination, with a rock-shaft provided with a loosely-mounted operating-gear and a spring connecting the gear and shaft, of a nut-holder mounted on said arm, substantially as set forth.

65 13. In a nut-tapping machine, the combina-

tion, with a nut-holder mounted to swing and having an end opening, of a fixed chute adapted to register with the said end opening, and an inclined vibrating chute discharging into the said fixed chute, substantially as shown and described.

70 14. In a nut-tapping machine, the combination, with a nut-holder mounted to swing and having an end opening, of a fixed chute adapted to register with the said end opening, and a fixed spring adapted to be engaged by the said nut-holder and serving to close the end opening of the said chute, substantially as shown and described.

75 15. In a nut-tapping machine, the combination, with a nut-holder, of a plate supporting the said nut-holder, spring-pressed jaws pivoted on the said plate, and a fixed plate having beveled arms adapted to be engaged by the said jaws to open the latter, substantially as shown and described.

80 16. In a nut-tapping machine, the combination, with a spindle mounted to rotate and to slide vertically, of a tap-holder held on the said spindle and adapted to support the tap, a rocking lever for imparting an upward sliding motion to the said spindle, and a plunger for disconnecting the tap and its holder when the spindle is on one of its upward movements, substantially as described.

85 17. In a nut-tapping machine, the combination, with a lever mounted to swing and provided with a ring, of a tap-holder passing centrally through the said ring and adapted to support the tap, and a second lever fulcrumed on the said tap-holder and adapted to travel with one end on the said ring, and a plunger held to slide in the said holder and operated by the said second lever to remove the tap from the holder, substantially as shown and described.

90 18. In a nut-tapping machine, the combination, with a lever mounted to swing and provided with a ring, of a tap-holder passing centrally through the said ring and adapted to support the tap, a second lever fulcrumed on the said tap-holder and adapted to travel with one end on the said ring, a plunger held to slide in the said holder and operated by the said second lever to remove the tap from the holder, and cams for actuating the said lever and the said holder to move both simultaneously upward, substantially as shown and described.

95 100 19. In a nut-tapping machine, the combination, with a lever mounted to swing and provided with a ring, of a tap-holder passing centrally through the said ring and adapted to support the tap, a second lever fulcrumed on the said tap-holder and adapted to travel with one end on the said ring, a plunger held to slide in the said holder and operated by the said second lever to remove the tap from the holder, cams for actuating the said lever and the said holder to move both simultaneously upward, and a spindle having a rotary

and a sliding motion and carrying the said holder, substantially as shown and described.

20. In a nut-tapping machine, the combination, with a spindle mounted to turn and to slide, of a lever connected with the said spindle to raise the same, and a cam operating on the said lever to raise the same, substantially as shown and described.

21. In a nut-tapping machine, the combination, with a spindle mounted to turn and to slide, of a lever connected with the said spindle to raise the same, a cam operating on the said lever to raise the same, and a spring pressing on the said spindle to move the same downward, substantially as shown and described.

22. In a nut-tapping machine, the combination, with a spindle mounted to turn and to slide, of a lever connected with the said spindle to raise the same, a cam operating on the said lever to raise the same, a finger held in the said cam, a toothed wheel actuated by the said finger and carrying a pin, and a shaft carrying an arm adapted to be engaged by the said pin to turn the said shaft, substantially as shown and described.

23. In a nut-tapping machine, the combination, with a spindle mounted to turn and to slide, of a lever connected with the said spindle to raise the same, a cam operating on the said lever to raise the same, a finger held in the said cam, a toothed wheel actuated by the said finger and carrying a pin, a shaft carrying an arm adapted to be engaged by the said pin to turn the said shaft, a cam held on the said shaft, and a lever actuated by the said cam for detaching the tap from the said spindle, substantially as shown and described.

24. In a nut-tapping machine, the combination, with a spindle mounted to turn and to slide, of a lever connected with the said spindle to raise the same, a cam operating on the said lever to raise the same, a finger held in the said cam, a toothed wheel actuated by the said finger and carrying a pin, a shaft carrying an arm adapted to be engaged by the said pin to turn the said shaft, a cam held on the said shaft, a lever actuated by the said cam for detaching the tap from the said spindle, and a detaching device connected with the holder of the said spindle and actuated from the said lever, substantially as shown and described.

25. In a nut-tapping machine, the combination, with a shaft having a slow-turning movement, of a cam held on the said shaft, a shifting lever actuated by the said cam, a clutch held to slide on and to turn with the said shaft and connected with the said shifting lever, and a gear-wheel having a constant rotary motion, mounted loosely on the said shaft and provided with a clutch adapted to be engaged by the said first-named clutch, substantially as shown and described.

26. In a nut-tapping machine, the combination, with a shaft having a slow-turning movement, of a cam held on the said shaft, a shifting lever actuated by the said cam, a clutch held to slide on and to turn with the said shaft and connected with the said shifting lever, and a gear-wheel having a constant rotary motion, mounted loosely on the said shaft and provided with a clutch adapted to be engaged by the said first-named clutch, substantially as shown and described.

ing lever actuated by the said cam, a clutch held to slide on and to turn with the said shaft and connected with the said shifting lever, a gear-wheel having a constant rotary motion, mounted loosely on the said shaft and provided with a clutch adapted to be engaged by the said first-named clutch, and a spring pressing on the said first-named clutch to force the latter suddenly in contact with the gear-wheel clutch, substantially as shown and described.

27. In a nut-tapping machine, the combination, with a shaft having an intermittent fast and slow rotary motion, of a cam-wheel secured on the said shaft and provided with a pin and a recess in its periphery, a lever adapted to be engaged by the said pin and provided with a segmental gear-wheel, a gear-wheel in mesh with the said segmental gear-wheel, a second shaft on which is mounted loosely the said gear-wheel, and a spring coiled on the said shaft and secured at one end to the said gear-wheel and at its other end connected with the said shaft, as set forth.

28. In a nut-tapping machine, the combination, with a shaft having an intermittent fast and slow rotary motion, of a cam-wheel secured on the said shaft and provided with a pin and a recess in its periphery, a lever adapted to be engaged by the said pin and provided with a segmental gear-wheel, a gear-wheel in mesh with the said segmental gear-wheel, a second shaft on which is mounted loosely the said gear-wheel, a spring coiled on the said shaft and secured at one end to the said gear-wheel and at its other end connected with the said shaft, and a segmental arm secured on the said shaft and carrying the nut-holder, substantially as shown and described.

29. In a nut-tapping machine, the combination, with a shaft having an intermittent fast and slow rotary motion, of a cam-wheel secured on the said shaft and provided with a pin and a recess in its periphery, a lever adapted to be engaged by the said pin and provided with a segmental gear-wheel, a gear-wheel in mesh with the said segmental gear-wheel, a second shaft on which is mounted loosely the said gear-wheel, a spring coiled on the said shaft and secured at one end to the said gear-wheel and at its other end connected with the said shaft, a segmental arm secured on the said shaft and carrying the nut-holder, and a tap-clamping device held on the said segmental arm and adapted to support the tap, substantially as shown and described.

30. In a nut-tapping machine, the combination, with a shaft having an intermittent fast and slow rotary motion, of a cam-wheel secured on the said shaft and provided with a pin and a recess in its periphery, a lever adapted to be engaged by the said pin and provided with a segmental gear-wheel, a gear-wheel in mesh with the said segmental gear-wheel.

wheel, a second shaft on which is mounted loosely the said gear-wheel, a spring coiled on the said shaft and secured at one end to the said gear-wheel and at its other end connected with the said shaft, a segmental arm secured on the said shaft and carrying the nut-holder, a tap-clamping device held on the said segmental arm and adapted to support

the tap, and a fixed plate for opening the said clamping device, substantially as shown and described.

CLARENCE L. CHAPMAN.
